(57) **CLAIM**

The ornamental design for a child resistant storage device, as shown and described.

DESCRIPTION

FIG. 1 is a top, front, left perspective view of a child resistant storage device;

FIG. 2 is a bottom, back, right perspective view thereof; FIG. 3 is a top view thereof;

FIG. 4 is a left side view thereof, with the right side a mirror image thereof;

FIG. 5 is a bottom view thereof;

FIG. 6 is a front view thereof; and,

FIG. 7 is a rear view thereof.

The broken lines in the figures depict portions of the child resistant storage device that form no part of the claimed design.

1 Claim, 3 Drawing Sheets
